UNITED STATES PATENT OFFICE.

JESSE ALEXANDER, OF BROOKLYN, NEW YORK.

DESIGN FOR A SPOOL FOR TYPE-WRITER RIBBONS AND TENSION-BANDS.

No. 38,857.

Specification for Design.

Patented Oct. 15, 1907.

Application filed August 3, 1905. Serial No. 272,615. Term of patent 14 years.

To all whom it may concern:

Be it known that I, JESSE ALEXANDER, a citizen of the United States, residing at Brooklyn, Kings county, State of New York, have invented a new, original, and ornamental Design for Spools for Type-Writer Ribbons and Tension-Bands, of which the following is a full, clear, and exact specification.

The figure is a perspective view of a spool embodying my design.

What I claim is:

The ornamental design for a spool for type-writer ribbons and tension bands as shown.

JESSE ALEXANDER.
